United States Patent Office.

FAYETTE S. ROBINSON, OF BOSTON, MASSACHUSETTS.

Letters Patent No. 76,945, dated April 21, 1868.

IMPROVEMENT IN LAMP-BURNERS.

The Schedule referred to in these Letters Patent and making part of the same.

TO ALL WHOM IT MAY CONCERN:

Be it known that I, FAYETTE S. ROBINSON, of the city of Boston, in the county of Suffolk, and State of Massachusetts, have invented a new and improved Burner for Kerosene-Lamps; and I do hereby declare the following to be a full and correct description of the same, reference being had to the accompanying drawings, in which—

Figure 1 is a vertical central section of the burner and chimney, taken transversely across the wick-tube.

Figure 2 is a bottom view of the burner.

Figure 3 is a bottom view of the deflector.

Figure 4 is a detail view, showing the mode of attaching the deflector to the chimney, and the chimney to the base-plate.

The same part is marked by the same letter wherever it occurs.

The nature of this invention consists in the new mode of supporting the deflector by attaching it to the inside of the chimney, of confining the chimney in place by centripetal holders, and of controlling the force of the draught by passing the air to the flame through a series of perforated media, so arranged as to deflect and break up the currents, all as hereinafter more particularly set forth.

To enable others to make and use my improved burner, I will proceed more particularly to describe its construction and mode of operation, referring to the drawings, on which A marks the screw-cup, B the wick-tube, and C the wick-elevator, all of the ordinary construction. D is the perforated base-plate with its edge turned down, as shown. E marks an intermediate perforated plate, the holes in which are oblong, and each surmounted by an arched strip of metal of the same width as the hole. This plate is made of a single-piece of metal struck up in a die. A current of air, passing upwards through the holes in E, would be deflected by the arched strips, and take a lateral direction. I contemplate substituting for this plate, in some cases, one or more thicknesses of wire gauze, the object of such interposed plate or perforated media being to deflect and break up the currents of air forming the draught, so that no sudden change in the force of the draught can take place, even when the lamp is exposed to wind, thus insuring great steadiness of flame. F marks the upper dome-shaped perforated plate through which the draught passes directly to the flame.

G, (see figs. 1, 3, and 4,) is the deflector, which is attached to the inside of the chimney H, in such a position that, when the chimney is placed on the lamp, the deflector shall be in its proper relation to the top of the wick-tube, as represented in fig. 1. On the under side of the deflector are attached three springs, d d d, reacting outwards, their ends being bent at right angles to form the three points e e e, as shown in fig. 3. These points, when the deflector is placed in its proper position in the chimney H, spring into grooves or recesses cut on the inside of the chimney to receive them, as shown in fig. 4.

H, figs. 1 and 4, is the chimney, which may be of any form not inconsistent with the attachment to it of the deflector. It has a flange or lip, f, around its bottom edge, which rests upon the base-plate D, and is held in place by the holders M, operated by the springs N, in the manner hereinafter described.

The mechanism for operating the centripetal holders M is clearly illustrated in figs. 2 and 4. These holders are of the shape shown in fig. 4. They slide on the bottom of the base-plate D, being held in place by slots in the edge of that plate through which they project, and by pins, g, passing up through slots in the body of plate D. Studs i, on the lower side of the holders, serve for the attachment of the spiral springs N N N, which tend to draw back the holders M towards the centre of the base-plate, and cause them to hold the chimney firmly and centre it correctly. The holders M are driven outwards, so as to release the chimney by the action of the sliding bar J, and the levers K and L. These levers have their fulcra on the pins b c, and are attached, at one end, to the bar J, a pin projecting from said bar passing through a slot in the end of each lever. The opposite end of each lever is in contact with a stud, i, on the bottom of one of the sliding holders M. A thumb-piece on the outer end of bar J affords the means of pressing it inwards to operate the levers and throw out the holders. The springs N counteract the levers K L, and draw in the holders when the pressure on bar J is relieved.

The advantages which I claim for this mode of construction are, security of the chimney, steadiness of light, and convenience in cleaning, trimming, and lighting.

Claims.

Having thus fully described my invention, what I claim, and desire to secure by Letters Patent, is—

1. In combination with the deflector G, the spring-points e, for the purpose of supporting the deflector by entering grooves or recesses in the chimney prepared to receive them, as described.
2. Confining the chimney and centring it by means of centripetal holders, constructed and operating as set forth.
3. The combination and arrangement of the slide J, levers K L, sliding holders M, and springs N, in the manner and for the purpose specified.

The above specification of my said invention signed and witnessed at Boston, this 23d day of January, A. D. 1868.

FAYETTE S. ROBINSON.
